UNITED STATES PATENT OFFICE.

FREDERICK A. STEVENSON, OF DETROIT, MICHIGAN, ASSIGNOR TO AMERICAN CAR AND FOUNDRY COMPANY, OF ST. LOUIS, MISSOURI, A CORPORATION OF NEW JERSEY.

TOGGLE MECHANISM.

1,276,437.

Specification of Letters Patent. Patented Aug. 20, 1918.

Application filed November 12, 1915. Serial No. 61,063.

To all whom it may concern:

Be it known that I, FREDERICK A. STEVENSON, residing at Detroit, Michigan, and being a citizen of the United States, have invented certain new and useful Improvements in Toggle Mechanism, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings:

Figure 1 is a longitudinal section through 20 a punching device illustrating an embodiment of my invention, and is taken on line 1—1 of Fig. 4.

Fig. 2 is a partial plan and horizontal section of the vertically slidable impulse 25 member of the punching device, the sectional portion being taken on line 2—2 of Fig. 1.

Fig. 3 is a horizontal section taken on line 3—3 of Fig. 1, showing the base plate and 30 the parts associated therewith principally in plan, some parts being broken away for added clearness.

Fig. 4 is a vertical transverse section taken on line 4—4 of Fig. 1, and discloses 35 part of the toggle mechanism of a plurality of punching units and means for rendering the latter effective.

Fig. 5 is a fragmentary sectional view taken on the anticlinal planes indicated by 40 line 5—5 of Fig. 1, and depicts other portions of the toggle mechanism.

Fig. 6 is another fragmentary section taken on line 6—6 of Fig. 4, further illustrating the means for rendering the toggle 45 mechanisms of the punching device effective.

Figs. 7 and 8 are detail views of the uppermost toggle leg.

Figs. 9 and 11 are also detail views, each illustrating one of the remaining toggle legs.

50 Fig. 10 is a detail view of the common pivotal member of the toggle mechanism,

its parts being separated to accentuate the individuality of each; and

Fig. 12 is a sectional view taken on line 12—12 of Fig. 4, and shows corresponding 55 ends of the arcuate flanges of the toggle legs slidably retained in one of the annular grooves in the common pivotal member.

This invention pertains to a toggle mechanism that is susceptible to embodiment in 60 a considerable variety of machines and in machine fixtures wherein a movable impulse member is depended upon to cause the actuation of another movable member not directly attached thereto. An example of 65 such an embodiment is illustrated in my two patents, one being for a punching machine, Patent No. 1,164,028, and the other for a channel punching machine, Serial No. 1,164,027, wherein the toggle mechanism is 70 claimed only in conjunction with other elements of the respective machines and not as an independent mechanism applicable in general machine design. Broadly, the invention comprehends any suitable fixed piv- 75 otal support, as one carried by or present in an appropriate base or on or in some fixed machine part, a movable member, which may be some type of slide in a guideway, a movable impulse-imparting member 80 and a toggle uniting these elements and possessing the peculiarities hereinafter set forth.

The modes of connecting the elements of the toggle mechanism with themselves and 85 with the parts associated with them are also features of the invention.

The arrangement of the parts is such that great power may be exerted to enable the tool to overcome any amount of resistance 90 work may develop, while the construction of the various elements insures an appropriate absorption by each of set up stresses eliminating any danger of collapse in the mechanism.

95 Such an assembly of associated members is proposed as will produce a strongly connected mechanism capable of permitting free, easy and harmonious action between its several parts, it being further contemplated to include a plurality of such mechanisms in a single device, and means

for selectively rendering any of the mechanisms effective or ineffective.

Other advantages becoming manifest hereinafter are, of course, to be understood as all 5 coming within the scope of the present invention.

In the drawings the invention has been shown as applied to a punching machine, but this is merely a typical application as 10 will later be pointed out. Referring to the parts of the illustrated example, 1 indicates a suitable base in or on which are bed portions 2. Arising at one end of each of said bed portions is an end wall, 3, which, if 15 desired, may connect a plurality of bed portions 2, upstanding side walls 4 extending inwardly from the end wall 3 in pairs and being appropriately spaced from each other.

Said side walls 4 are provided along their 20 top edges for a suitable distance with inwardly extending horizontal flanges 5, those of companion side walls projecting toward each. The vertical side walls 4 and the bed 2 of each punching unit are provided with 25 thickened portions, preferably co-extensive with the length of flanges 5, these thickened portions and the undersides of said flanges being machined to form a guideway. In the latter is seated a reciprocatory head 6, which 30 may be shaped to form any suitable type of slide, and is retained in place by the flanges 5, which are shown to overhang said head 6.

Reciprocatory head 6 has means such as 35 lug 7, for the attachment thereto of a tool-holder, the latter in the present instance being shown as a punch-block 8, provided with a lug 9 adapted to be clamped to lug 7 of head 6 by bolt 10, or other suitable means. That 40 the punch block 8, or other tool-holder, may be undeviatingly positioned in its normal line of travel, it is provided with tongues 11 adapted to fit and be slid into grooves 12 in the reciprocatory head 6, and when so fitted 45 and lugs 7 and 9 are bolted together the punch block 8 is reliably held, as may be seen in Figs. 1 and 3. In practice, a number of punch blocks having lugs 9 of varying length may comprise a set for each punching device and permit the setting of a punch 50 13 at different altitudes. Said punch 13 is secured to a punch stem 14 retained in said tool-holder or punch block 8, which stem is provided with a head which bears against a 55 backing-plate 15 secured to reciprocatory head 6.

Alined with punch 13 of each punching unit and having a common axis therewith is a die 16 mounted in a die-block 17, the latter 60 being adapted to fit and be slid into a groove in a standard 18, at the end of bed 2 opposite that from which end wall 3 arises. Die block 17 is furnished with a lug 19, which by such means as a bolt 20 secures said die-block to standard 18. In a given set-up the

lugs 9 and 19 of the punch and die-blocks, respectively, are proportioned to properly line the punch 13 and die 16, and die block 17 is provided with a passage 21 communicating with a passage 22 in standard 18, 70 whereby slugs punched from the work find an exit from the punching device.

That portion of reciprocatory head 6 to which backing-plate 15 is attached is rugged and block-like and, preferably, is of L-shaped cross-section, the upstanding leg of the L being materially thicker than the horizontal leg, the reciprocatory head 6 also having outer side walls 23 between which the L-shaped portion is located, as best seen in 80 Figs. 1, 3 and 5.

The horizontal leg and the bottoms of the side walls 23 of the reciprocatory head 6 are finished to slide on the thickened portion of bed 2, while the outer faces of said side 85 walls 23 slide along the inner faces of the thickened portions of the side walls 4 of base 1. The top edges of side walls 23 have sliding engagement with the under surfaces of flanges 5 of the base side walls 4. Thus, 90 the reciprocatory head is adapted to slide back and forth in the guideway.

To impart sliding movement to head 6, a toggle mechanism is provided and comprises, in the form shown, triplicate legs and 95 a common-pivotal member connected with and connecting said toggle legs, which legs are similar to each other except for such modifications as their associated parts make necessary or advisable. One toggle leg 24 100 has a fixed pivotal connection with base 1, another toggle leg 25 is pivotally connected with reciprocatory head 6 and a third toggle leg 26 extends upwardly to have a relatively 105 slideable connection with an impulse-giving member or top plate 27 alterable to a fixed pivotal connection, all of said toggle legs being rotatively united about said common pivotal member, which also forms the central member of the toggle mechanism. 110

Said common pivotal member comprises a pintle 28 provided at its outer end with an annular flange 29 and a disk-like cap 30 115 removably connected to the opposite end of said pintle 28, preferably by means of an integral threaded stud 31 projecting from cap 30 and entering a threaded recess in the adjacent end of pintle 28.

Both said annular flange 29 and the cap 30 contain an annular groove 32, the inner diameter of which corresponds to that of said pintle 28 and the outer diameter of which is sufficient to envelop the adjacent ends of arcuate flanges 33 carried by the inner ends of the toggle legs 24, 25 and 26. Arcuate 125 flanges 33 conform to the curvature of pintle 28 and extends therealong beyond the sides of the toggle legs and project at opposite ends into the annular grooves 32 in annular flange 29 and cap 30, being securely held in 130

said grooves by the surrounding metal, but permitted to have curvilinear sliding movement therein.

Each of said toggle legs 24, 25 and 26 has at its outer end a cylindrical or other shaped barrel 34 disposed parallel to the arcuate flanges 33, and which is drilled or otherwise apertured for the passage of a bolt or pin. The barrel ends are countersunk to receive the reduced ends of removable hardened steel journals 35, which are centrally drilled to continue the passages in the barrel 34.

Barrel 34 of toggle leg 24 bears against a conforming seat 36 in the end wall 3 of the punching unit to which the toggle mechanism belongs, and its extensions or journals 35 are seated in bearings created by making cylindrical holes in companion side walls 4 of base 1. Journals 35 are retained seated in the ends of barrel 34 by a bolt and nut 37. The axis of barrel 34 and the journals 35 of toggle leg 24 is therefore fixed and said toggle leg is restricted to a rotary movement thereabout.

At or near the junction of the inner angle of the L-shaped portion of the reciprocatory head 6 is formed a similar seat 38 for the barrel 34 of toggle leg 25, the journals 35 seated in the ends of which barrel projecting into bearings formed by cylindrical holes in the side walls 23 of the reciprocatory head 6. A pin 39 passes through barrel 34 and journals 35 of toggle leg 25, but is unheaded as the side walls 4 upstanding from base 1 on either side of head 6 prevent the dislodgment of pin 39 in any of the positions of said head. Toggle leg 25 manifestly rotates about the axis of its barrel and journals, and said axis travels back and forth with said head.

Impulse member 27 is designed to receive motion from any proper agent, it being a common practice to bolt it to the slide of a punching machine when the invention is employed in connection with such class of devices. One end of impulse member 27 rides over a guide 40 mounted in and extending upwardly from base 1, and at the opposite end impulse member 27 is provided with a depending pair of spaced lips 41 for each punching unit. Toggle leg 26 of the toggle mechanism under consideration extends upwardly between loops 41 associated with said toggle mechanism and an end of its barrel 34 itself forms a bearing seated in one of the loops 41, such as the inner one. A removable journal 35 extends into the companion or outer loop 41 and is held seated in barrel 34 by a bolt and nut 42.

Between companion loops 41 and above barrel 34 of toggle leg 26 is a chamber 43 in which is a toggle block 44, resting upon the barrel 34 of said toggle leg 26. The punching devices or units may be used singly or combined in groups in the same machine,

and when singly used a single gag may be inserted into chamber 43 into a space that is present below the top wall of said chamber and the upper surface of toggle block 44 contained therein, filling said space. A downward movement would then actuate said toggle mechanism to operate the tool affected thereby.

Individual gags may be used also when punching units are arranged in groups, if desired, but a gagging device has been illustrated which has given eminent satisfaction in practice. As shown, it comprises a horizontally disposed gag 45 in the form of a rectangular bar depressed or cut out centrally on its upper side. In the cut-out portion of the bar is a hole in which is seated a pin 46 riveted to shifting bar 47. The latter extends away from gag 45 and at its opposite end is secured, as by bolts, or rivets, to a gag-handle 48, which extends in opposite directions through and beyond the sides of impulse member 27.

Notches 49 and 50 are formed in the under side of gag handle 48 outside of impulse member 27, and attached to the outer sides of said impulse member are spring detents 51 and 52 adapted to be engaged by notches 49 and 50, respectively, when the gag-handle 48 is moved in one direction or the other.

Gag 45 is located between two punching units, as shown, and is supported by a bracket 53 secured to wall 54 of impulse member 27, as by screws. Said gag has its opposite ends directed toward chambers 43 in impulse member 27 and projects slightly into each, but not far enough to extend over the toggle block 44 of the toggle mechanism of either punching unit, when gag 45 is not in use.

But, when gag-handle 48 is moved to cause, say, notch 49 to engage its spring detent 51, shifting bar 47 projects one end of gag 45 into chamber 43, shown at the right in Fig. 4 and at the top in Fig. 2, filling the space between the under side of the top wall of impulse member 27 and the top of toggle block 44 in that chamber. Moving gag handle 48 in the opposite direction so that notch 50 engages detent 52, the opposite end of gag 45 enters chamber 43 of the other punching unit, gagging the latter in like manner.

When either punching unit is so gagged and impulse member 27 is moved downwardly by any agent, such as the slide (not shown) of a punching machine, toggle leg 26 of the affected toggle mechanism is forced downwardly by toggle block 44, in turn pressing on pintle 28 of the common pivotal member and moving the latter also downwardly. Toggle legs 24 and 25, which are normally both inclined upwardly toward said common pivotal member and connected therewith as described, are both rotated

downwardly becoming straightened with respect to each other as they progress, and thus driving reciprocatory head 6 toward work. Head 6 carries punch 13 to and 5 through work and into die 16. A raising of impulse member 27 returns the toggle mechanism to the position shown, retracting head 6 and tool 13. When gag 45 is in the position shown in the drawings, or when it 10 is inserted into one chamber 43 to gag one toggle mechanism and not the other, the unggaged toggle mechanism is not operated. Upon a downward movement of impulse member 27, the space in the chamber 43 for 15 the unggaged toggle mechanism, being unoccupied by the end of gag 45, permits the top wall of said chamber to move down a distance equal to the stroke of said impulse member without contacting with toggle block 44. Hence, in view of this lost motion, no movement is given to this toggle mechanism. It has been stated that the 20 punching device illustrated is but a typical application of the invention. That it is fully intended to apply the operating mechanism herein described, either to operate a 25 tool or to transmit motion from one part of a machine to another part, is to be clearly understood. Also, instead of operating a 30 punch, the head 6 may actuate a drawing and forming die set, or it may be used to work embossing dies.

The mechanism may be used for applying pressure in any kind of machine requiring 35 it, and groups of such mechanisms may be arranged to apply pressure either simultaneously on a movable member of considerable area or upon a group of tools and in the latter case in unison or in any order 40 desired.

I claim:-

1. In combination in a mechanism of the class described, a movable member, an impulse member, a toggle mechanism connected 45 positively with said movable member and continuously retained by said impulse member being at times loosely and inoperatively connected therewith, and means for positively and operably connecting said toggle 50 mechanism and impulse member at will.

2. In combination in a mechanism of the class described, a fixed support and a movable member, a toggle mechanism connecting the same and provided with an operating member, an impulse member having a 55 lost motion connection with the latter and independently operable means for converting said lost motion connection to a positive connection.

60 3. In combination in a mechanism of the class described, fixed and movable members, spaced bearings in each, and a toggle mechanism comprising commonly pivoted legs or links having outer portions extending 65 between said spaced bearings and separate

journals projecting from opposite sides of said outer portions into said bearings, and means securing each separate journal to a side of one of said legs or links.

4. In combination in a mechanism of the class described, fixed and movable members, spaced bearings therein, and a toggle mechanism comprising commonly pivoted legs having portions extending between said bearings and removable journals projecting from said portions and seated in said bearings and means affixing said journals to said legs protected from shearing stresses.

5. In combination in a mechanism of the class described, a stationary member having an end wall and side walls, a seat in the former and bearings in the latter, said seat and bearings being spaced longitudinally of a single axis, a slidable member, toggle mechanism comprising commonly pivoted legs one pivotally connected with said slid- 85 able member and another seated in said seat and journaled in said bearings, and means for operating said toggle mechanism.

6. In combination in a mechanism of the class described, a stationary member, a movable member, a movable impulse member the latter being provided with a chamber, a pair of bearing loops depending therebelow, a toggle mechanism connecting said stationary and movable members and being provided with a leg extending between said bearing loops, journals projecting from said leg into and movable in said loops, a device in said chamber bearing on said leg and means adapted to be projected between a wall of said chamber and said device to cause said impulse member to definitely position the journals in said loops and to operate said toggle mechanism.

7. In combination in a mechanism of the class described a movable impulse member provided with a chamber, a spaced pair of bearing loops depending therebelow, a toggle mechanism adapted to operate another 110 movable member and being provided with a leg extending between said bearing loops, journals projecting from said leg into and movable in said loops one of said journals being removably held to said leg, a device 115 in said chamber bearing on said leg and adapted at times to be held thereby against movement with said impulse member and means adapted to move said impulse member and device together at will to definitely position said journals in said loops and to operate said toggle mechanism.

8. In combination in a mechanism of the class described, a movable impulse member provided with a chamber, a toggle mechanism adapted to operate another movable member and provided with a leg connected in slidable relation with said impulse member, a device in said chamber bearing on said leg, a gag normally out of alignment 125 130

with said device, means supporting said gag from said impulse member, shifting means connected with said gag, means for moving the shifting means such movement being adapted to project said gag between a wall of said chamber and said device to cause said toggle mechanism to be operated by movement of said impulse member.

9. In combination in a mechanism of the 10 class described, a common pivotal member having a cylindrical body portion and portions provided with annular grooves, toggle legs or links connected with said common pivotal member to have relatively rotative interlocking relation therewith, one 15 of said legs or links having at one end an arcuate flange adapted to bear on said cylindrical body portion and extending from opposite sides of the last mentioned leg and into said annular grooves and provided at its opposite end with a cylindrical barrel portion recessed at one end and forming a journal at the other end; a removable journal fitted to the recessed end and means

securing said removable journal to said barrel portion. 25

10. In combination in a mechanism of the class described, a common pivotal member having a cylindrical body portion and portions provided with annular grooves, toggle 30 legs or links connected with said common pivotal member to have relatively rotative interlocking relation therewith and each having at one end an arcuate flange adapted to bear on said cylindrical body portion and 35 extending from opposite sides of said legs into said annular grooves, cylindrical barrel portions at the opposite ends of said legs recessed at their ends, removable journals fitted to the recessed ends and means securing the removable journals to said recessed ends. 40

In witness whereof I have hereunto set my hand in the presence of two witnesses.

FREDERICK A. STEVENSON.
